Herman L Greve

Frank M. Shibley
BY
ATTORNEY

UNITED STATES PATENT OFFICE.

HERMAN L. GREVE, OF NEW YORK, N. Y., ASSIGNOR TO INTERNATIONAL MAILING TUBE AND WRAPPER COMPANY, OF BROOKLYN, NEW YORK, A CORPORATION.

MAILING WRAPPER.

Application filed October 2, 1920. Serial No. 414,221

To all whom it may concern:

Be it known that I, HERMAN L. GREVE, a citizen of the United States, and resident of New York city, in the county of Kings and State of New York, have invented certain new and useful Improvements in Mailing Wrappers, of which the following is a specification.

My invention relates to mailing wrappers. 10 The object of my invention is to provide means for fastening the ends of a wrapper together at a low cost and in an expeditious manner.

Referring to the drawings which form a 15 part of this specification,

Figure 1 is a perspective view of a portion of a wrapper shown partly in section, the ends of which are held together by a fastening device hereinafter referred to as a coupling, and embodying my invention.

Figure 2 is a perspective view of the coupling which I prefer to make of metal, and for thin flexible wrappers I prefer to make the coupling of thin flexible metal as it is 25 easier to perform the operation of coupling the ends of the wrapper together when the metal is tempered to give spring quality so that the end of the coupling will bend slightly as it is inserted through the slot 30 formed in the wrapper.

Figure 3 is a perspective view of a modified construction, two hooks being formed in place of one as shown in Figure 1.

Figure 4 is a longitudinal sectional view 35 of the wrapper ends and a side view of the coupling illustrated in Figure 3.

The drawings are made on an enlarged scale, the coupling being made about one quarter the size thereof in practice for use 40 with medium sized packages.

A and A' indicate the respective ends of a mailing wrapper made of tough paper, and B, indicates the coupling which is formed by a punch and die process, and 45 comprises a strip of metal embodying a hook B' located near the middle of the strip and offset therefrom a distance slightly greater than the thickness of the wrapper. I also prefer to bend the strip to form an 50 offset on a line where the base of the hook B' joins the strip as shown at B² to permit the wrapper to lay smooth at this point and also to act as an abutment for the wrapper and to prevent it from sliding toward the 55 end A.

The strip B is provided with a V-shaped end B³ which is passed through one end of the wrapper and clinched thereon as illustrated in Figure 1, and the end B⁴ is passed through a slot C formed in the wrapper, and extends 60 beyond said slot on the inner side of the wrapper for a short distance. It will be noted that the length of the slot C is greater than the width of the coupling, thus permitting the end B⁴ to be easily slipped 65 through the slot in the act of coupling the ends of the wrapper together and permitting the hook B¹ to also pass through the slot and then by a reverse movement cause the hook to engage the edge of the wrapper as 70 illustrated.

In practice the act of coupling the ends of the wrapper together is almost instantaneous and after they are coupled, the end B⁴ prevents them from becoming easily or 75 accidentally uncoupled, as a portion of the coupling under the wrapper extends on each side of the slot C.

The quickness with which the ends may 80 be coupled is a very important matter where a large number of wrappers are to be coupled.

As shown in Figures 1 and 2 the coupling is provided with a single hook indicated by B'. In the modified form shown in Figures 85 3 and 4, the two hooks D and D' respectively are shown, formed at each side of the strip B instead of at the middle thereof, the function however being the same.

Having thus described my invention, I 90 claim as new:

1. A wrapper comprising a sheet having a slot therein and a coupling formed of a strip of metal having a hook offset from the plane surface of the strip located between 95 its ends and adapted to pass through the slot formed in said sheet.

2. A wrapper comprising a sheet having a slot therein and a coupling formed of a strip of metal having a hook offset from the plane surface of the strip located between 100 its ends and adapted to pass through the slot formed in said sheet, one of the end portions of said strip being offset to provide 105 an abutment on the strip.

3. A coupling for a mailing wrapper comprising a body portion, an end portion lying in a plane substantially parallel to the plane 110 of the body portion and a hook extending

beneath the body portion and an end portion extending substantially perpendicular to the body portion.

4. A coupling for a mailing wrapper comprising a body portion, an end portion lying in a different plane from the plane of the body portion, a shoulder uniting the body portion to the end portion, a hook extending from the said shoulder in a different plane 10 from the body portion and a V-shaped end

portion extending substantially perpendicular to the body portion.

Signed at New York city, in the county of Kings and State of New York, this 27th day of August, A. D., 1920.

HERMAN L. GREVE.
